UNITED STATES PATENT OFFICE.

THEODORE M. WILSON, OF CANTON, ILLINOIS.

DEVICE FOR PACKING CIGARS.

SPECIFICATION forming part of Letters Patent No. 361,604, dated April 19, 1887.

Application filed January 10, 1884. Renewed December 13, 1886. Serial No. 221,388. (Model.)

To all whom it may concern:

Be it known that I, THEODORE M. WILSON, of Canton, in the county of Fulton, in the State of Illinois, have invented an Improved 5 Device for Packing Cigars; and I do hereby declare that the following is a full, clear, and exact description thereof, reference being had to the annexed drawings, making a part of this specification, in which like letters of reference refer to like parts, and in which—

Figure 1 represents a perspective view of the same; Fig. 2, a section; Fig. 3, a view of under side of the device, and Fig. 4 a perspective view showing the mode of removing 15 and transferring the compressed cigars to the box.

The object of this invention is the construction of a device by means of which cigars may be reduced in bulk by compression and transferred, when so reduced, to the boxes in which it is customary to pack them.

My invention consists of a box open at the top and one side, having means whereby it may be longitudinally adjusted, and also having 25 a wedge by which to compress the cigars when in said box, as well as means whereby to remove the cigars and retain them in the reduced bulk until they have been placed in the cigar-box.

In the drawings, A is the box, having extensible bottom B and side A'. Said side A' is formed of two parts, A² and A³. The part A² is fast to the end piece C, and the other part, A³, is fast to the end piece C. When these 35 two end pieces, C' and C, are moved toward or from each other, the two parts A² and A³ of the side A' slide the one on the other. The extensible bottom is formed in four pieces, one of which, B', is firmly secured to the end piece 40 C', two of which, B², are fastened to the other end, C, and between which slides the strip B'. Upon these three strips B' B² B² is the thin broad piece B³, fastened to the end C' and extending to within a short distance of the end 45 C. This serves to make the bottom entire.

The movable block D, sliding between the side A' and partial side piece, A³, is drawn toward the end C by an elastic or spring, D'. The screw D² regulates the nearness of approach to the end C of said block D. Between 50 this block D and the end C is the wedge E,

having a portion of its lower edge cut away, so that it may not rest upon the screw D², but upon the bottom B. To permit the ready grasping and removal of the wedge E from 55 between the block D and end piece C, it is recessed at E' and the end C is cut away, as shown in Fig. 1.

The means by which the box A is fastened at any desired point of longitudinal adjustment consists of a bolt, G, passing through the strips B' B² B² of the bottom B, as shown in Fig. 3, the central strip, B', being slotted longitudinally to permit the required movement. This bolt G, having its head G² at the 60 outside of one strip B² and its thumb-nut G' at the outside of the other strip B², enables the said strips to be so closely drawn together as to firmly clamp between them the strip B', and thus hold the box A when adjusted. 70

L is a rectangular piece of board approximately equal in length and breadth to the corresponding dimensions of the cigar-box.

R is a tape or ribbon, the use of which is hereinafter described.

In using this device the tape R is first put into the box A, from end to end at its center, but projecting therefrom, as shown in Fig. 2. The wedge E being in place between the block D and the end piece C, the nut G' is loosened 80 and the box A shortened or lengthened until the end C' and the block D would just touch the ends of the board L if placed therein. The nut G' is then tightened and the wedge E removed. The block D then rests against the 85 end of the screw D², which is turned until a row of cigars laid side by side upon the bottom B in the number wished shall touch loosely the side of the said block D and the end C' of the box A. The cigars are now placed in the box 90 A upon the tape R until a sufficient number of horizontal rows or layers are in. The board L being laid upon the cigars, the wedge E is pressed firmly down in between the block D and the end piece C, and said block caused, 95 therefore, to move forward and compress the cigars into a smaller longitudinal space. By means of a press or other force not necessary to describe, the board L is crowded downward until the cigars are in a suitable degree of vertical compression, and while thus impressed the ends of the tape R are brought over the 100

board L and firmly gripped by the hand. Now, removing the wedge E, the block D flies back, the cigars and board L are raised by the hold on the tape R and transferred bodily to the 5 cigar-box, from which the board L is removed, the tape R pulled out, and the work is done. For the same lot of cigars further adjustment of the screw D² and length of the box A is of course unnecessary. The adjustment is only 10 required with different sizes of cigar-boxes and thickness of cigars.

What I claim as my invention, and for which I desire Letters Patent, is as follows:

1. In a cigar-packer, a box consisting of a 15 side, bottom, and two ends, in combination with a block fitting transversely in said box and adapted to be moved longitudinally therein, and a wedge arranged to be impressed between said block and the adjacent end of said 20 box, whereby said block is forced against and suitably compresses the cigars placed in the box.

2. In a cigar-packer, a box consisting of a side, bottom, and two ends, said box being so 25 arranged as to permit the ends to be longitudinally adjusted, in combination with the block D, longitudinally movable in said box, and the wedge E, adapted to be inserted between said block and the adjacent end of the box, substantially as and for the purpose set forth.

3. In a cigar-packer, a box consisting of a side, bottom, and two ends, in combination with the block D, fitting transversely in said 35 box and capable of being moved longitudinally therein, the elastic D', for retracting said block toward the adjacent end of the box, the screw D², for limiting said retraction of said block, and the wedge E, adapted to be inserted between said block and the adjacent end of the 40 said box, as and for the purpose herein described.

4. In a cigar-packer, the box A, consisting of a side, bottom, and two ends, said side being formed of two pieces, A² A³, adapted to slide upon each other, said bottom being formed of the strips B' B³, fastened to the end C' of said ends, and of the strips B² B², fastened to the other end, C, said strip B³ being arranged to slide upon the strips B² B², and the strip B' being arranged to slide between said strips B², 45 in combination with clamping mechanism for securing together said strips at any desired point of adjustment, substantially as and for the purpose specified.

5. In a cigar-packer, the box A, consisting of a side, bottom, and two ends, said side being formed of two parts, A² and A³, one fastened to the end piece C' of said ends and the other, A³, to the end C of said ends, said bottom being formed of the strips B' B³, fastened to the said end C', 60 and of the two strips B², fastened to the end C, said strip B³ being arranged to slide upon said two strips and the strip B' between said two strips, in combination with a block or false end capable of being moved longitudinally in said 65 box, mechanism for forcibly moving said block toward its non-adjacent end, and the bolt G, passing through transverse slots G³ in said strips B' B² B³, and a thumb-nut, G', for said bolt, whereby said box can be clamped at any 70 desired point of longitudinal adjustment, as set forth.

In testimony that I claim the foregoing invention I have hereunto set my hand this 15th day of December, 1883.

THEODORE M. WILSON.
